ABSTRACT OF THE DISCLOSURE

A hand tool having a slender pin-sized plunger extending through a hollow slide with a socket-sized ferrule. Coil springs bias against travel of the slide between extended and retracted positions with respect to the plunger. The extended position may be locked by rotation of the slide to engage a bayonet pin within a retaining J-slot. Pin removal is by reception of a pin in the ferrule at the extended position and pushing outward against the pin shoulder. Socket removal is by release of the extended position and insertion of the plunger for pushing at the bottom of the socket, the ferrule retracting along the plunger and providing protection and compressive bracing thereof.

SUMMARY OF THE INVENTION

This invention relates generally to contact removal tools, and with more particularity, to a combination tool for removal of both pin and socket contacts.

Multiple pin and socket contacts have been provided in some of the individual electrical connectors presently available. For example, as many as 85 contacts have been provided in a single connector having a one inch diameter. As may be visualized, the pin and socket contacts are closely spaced in a dense concentration. Now it is often desirable to remove and replace selected individual contacts. Thus, the connectors are provided with contact retention devices to facilitate removal and replacement, for example, as disclosed in Pat. No. 3,477,061 issued on Nov. 4, 1969 to C. D. Stephenson. There, removal of the pin and socket contacts is accomplished by simply pushing the contacts back through the resilient retention device. It may be appreciated, of course, that a narrow tool is required because of the close spacing of the contacts.

The pin and socket contacts are themselves quite tiny and it is desirable to be able to remove them without damage. The most feasible tool for damage-free removal of the socket contacts has been found to be a slender plunger which may be inserted into the socket to push against the bottom thereof. Likewise, damage-free removal of pin contacts may be accomplished by a narrow ferrule which receives the pin to push against the pin shoulders. Separate individual tools, a plunger for the socket and a ferrule for the pin, have been utilized in the past.

Unfortunately, the required narrowness and length of the tools makes them highly susceptible to damage. It may be appreciated that the plunger utilized in socket removal is often no more than a stiff wire, which is readily bent and damaged. Furthermore, it is often a nuisance to have to change from one tool to another, since this requires the technician to take his eye off the relative positions of a pin vis-a-vis a socket both of which are desired to be removed. It may be appreciated, that with a multiplicity of densely packed contacts, relocation of the particular contact after a tool change may be time consuming.

Therefore, to overcome the foregoing and other difficulties of the prior art, a new and improved pin and socket removal tool is required. The present invention

envisioned a combination tool which may be utilized for the removal of both pins and sockets. In accordance with the present invention, a tool is provided by a hollow tubular body, adapted to be held manually, with slide and plunger members extending therefrom. The plunger is bottomed in the body and extends through an axial bore through the slide. Coil springs within the tubular body bias against travel of the slide between extended and retracted positions. The slide is locked at an extended position with a ferrule portion thereof beyond the plunger by rotation of the slide and its bayonet pin into a transverse J-slot in the body. A pin contact may then be received within the ferrule for removal by pushing against the pin shoulders. The plunger within the axial bore provides compressive bracing for the slide and ferrule. Release of the bayonet pin from the J-slot will allow a retraction of the slide against the coil spring bias for insertion of the plunger into a socket. Removal is by pushing against the bottom of the socket with the plunger, the ferrule and slide providing protection and compressive bracing therefore.

Thus, one of the objects of this invention is to provide a pin and socket removal tool.

It is an object of this invention to provide a combination tool which may be utilized in removal of both pin and socket contacts.

Another object is to provide a tool capable of contact removal without damage to the contacts or contact retention device, and without disturbance of neighboring contacts.

Still another object is to provide a combination tool having one member for removal of sockets and another member for removal of pins, wherein each member compressively braces the other during contact removal.

Also, an object of this invention is a pin and socket removal tool which may be readily assembled and disassembled to facilitate replacement of various members therein.

Yet another object is the provision of a sturdy, simple hand tool which is versatile for removal of both pins and sockets.

An object of this invention is to provide a combination pin and socket removal tool wherein the socket removal member is protected at all times.

Furthermore, it is an object to provide a pin and socket removal tool comprised of members which are readily assembled and susceptible to economical mass production manufacturing techniques.

Further and other objects, and a more complete understanding of the invention may be had by referring to the following description and claims, taken in conjunction with the accompanying drawings.

DESCRIPTION OF THE DRAWINGS

For the purpose of illustrating the invention, there are shown in the drawings a form which is presently preferred, it being understood, however, that this invention is not necessarily limited to the precise arrangement and instrumentality there shown.

FIG. 1 is a plan view of a pin and socket removal tool according to the present invention.

FIG. 2 is a side elevation of the pin and socket removal tool shown in FIG. 1, with a protective cap removed therefrom.

FIG. 3 is an enlargement of the tool shown in FIG. 2, with a handle covering thereof removed.

FIG. 4 is a perspective view illustrating pin removal by the tool of the present invention.

FIG. 5 is an enlarged and broken sectional view of the tool shown in FIG. 3.

FIG. 6 is an enlarged and broken section of the tool shown in FIG. 3 illustrating the relative disposition of parts during the removal of a socket contact.

FIG. 7 is an enlarged and broken section of a part of the tool shown in FIG. 3 illustrating the relative disposition of parts during removal of a pin contact.

DESCRIPTION OF THE PREFERRED EMBODIMENT

Referring now to the drawings in detail, where like numerals indicate like elements, there is shown in FIG. 1 an illustration of a pin and socket removal tool according to the present invention indicated generally by the numeral 10. A protective handle covering 15 and a protective cap 18 are provided of a material such as plastic which may be readily shaped into a compact and attractive configuration, as shown. The cap 18 is readily removable, as indicated in FIG. 2, and the handle covering 15 may include an inner end 17 shaped for mating reception of cap 18 and gripping areas 19 so that the tool 10 may be securely held.

The body member 20, shown in FIG. 3, has an interior portion 21 which may be cylindrically shaped and of a diameter for a tight force fit within the handle covering 15. An exterior portion 22 of body member 20 extends without the handle covering 15 and is visible in FIG. 2.

As shown in FIG. 3, the exterior portion 22 may be enlarged with respect to the interior portion 21 to provide a ledge 23 which abuts against the inner end 17 of the handle covering 15. The external portion 22 may be chamfered as at 24 to provide a neat appearance and to assist in seating of the protective cap 18 on the inner end 17 of handle covering 15.

Reference is now made to the cross-section of FIG. 5 for a description of the interior of body member 20 and associated parts. As shown, the body member 20 has an interior chamber 25 which may be a hollow cylinder. The chamber 25 is open at one end through aperture 26 in a retention collar 27 formed integrally, by machining or the like, within external portion 22. The opposite end of chamber 25 is closed by removable plug 28. A transverse pin 29 extends, as shown, through aligned openings in the body 20 and plug 28 for retention of the body member 20 and plug 28 together. The removable plug 28 includes an integral holder sleeve portion 30 of a reduced diameter with respect to the chamber 25. As shown by the cross-section of FIG. 5 the holder sleeve 30 projects inwardly into the chamber and has a bore 31 open to the chamber 25. Bore 31 terminates at a bottom 32 where the sleeve 30 is solid.

As shown best in FIG. 3 the body 20 has an elongated slot 33 extending longitudinally of the body interior portion 21. The forward end of the slot 33, towards the exterior body portion 22, is joined by a J-slot 34 which is transversely disposed with respect to the body member 20, as shown. Note that the slots 33, 34, extend through the wall of the interior portion 21 to the interior cavity 25, as shown by the cross-sections of FIGS. 5 and 6. Preferably, the body member 20 and its associated plug member 28 and retention pin 29 are machined of a durable metal, such as steel.

A slide member 40 is received within the chamber 25 for longitudinal travel therein, and thus has a transverse size corresponding to that of the chamber 25, as may be best visualized with reference to FIGS. 5 through 7. A spring guide surface 41 and bearing surface 42 may be provided at the interior of the slide member 40 by boring one end thereof as shown. The opposite end of the slide member 40 has a reduced portion 44 of a size which may be slidably received in the aperture 26 through retention collar 27. Reduced portion 44 extends without the body member 20 as shown in the figures. Slide member 40 presents a bearing ledge 45 opposite the retention collar 27, at the point of reduction to the reduced portion 44. The reduced portion 44 is further reduced at its outer-

most tip to provide a ferrule portion 46. The length and inside diameter of the ferrule portion 46 are chosen in accordance with the size of pin contacts which are to be removed, as will be come apparent in the following description. An axial bore 47 runs the length of the slide member 40 to the chamber 25. The axial bore 47 may include a countersink 48 within the reduced portion 44, as shown. A knurled surface 49, which is shown in FIG. 3, is provided for gripping of the reduced portion 44.

A long and slender plunger 60 is received within the bore 47, and extends through countersink 48 and chamber 25 of the slide member 40. Since the plunger member 60 is to be received within somewhat tiny socket contacts which are to be removed, a slender and stiff wire has been found ideal, for example 11 gauge nickel plated music wire (O.D. 0.026"). The plunger member 60 has a squared bearing tip 61 which engages bottom 32 of the holder sleeve 30, as illustrated in FIG. 5. A resilient insert 65, of nylon or other resilient material, is provided within the bore 31 of the holder sleeve 30 to securely hold plunger member 60, yet allowing removal and replacement thereof.

Lock means for holding the plunger member 40 in an extended position with respect to the plunger member 60 may be provided by a bayonet pin 70 extending radially from the slide member 40 for engagement within the elongated slot 33 and J-slot 34. The bayonet pin 70 may extend from a radial bore 72 in the slide member 40. Naturally, the bayonet pin 70 is sized and shaped to slide freely along the elongated slot 33 and J-slot 34 to allow the slide member 40 to travel between retracted and extended positions with respect to the plunger member 60.

A first bias means urging the slide member 40 toward an extended position with the ferrule portion 46 extending beyond the tip 62 of plunger member 60, is provided by the coil spring 80 which is compressed between the bearing surface 42 of slide member 40 and the end plug 28. Note that the diameter of the coil spring 80 is sufficient to receive the holder sleeve 30 therein, as indicated in FIGS. 5 and 6. On the other hand, the outside diameter of spring 80 is less than that of the spring guide surface 41 for reception therein within the slide member 40.

A second bias means is provided to urge the slide, against the bias of coil spring 80, toward a retracted position exposing the tip 62 of the plunger member 60. Coil spring 85 provides the second bias means by compression thereof between the retention collar 27 of the body member 40 and the ledge 45 of the slide member 40. The inside diameter of coil spring 85 is sufficient to receive the reduced portion 44 of slide member 40 and is less than the inside diameter of the interior cavity 25 of body member 20, as shown in FIG. 5. Preferably, the length and the strength of the coil springs 80, 85 are chosen to balance with the slide member 40 in a position exposing a short length of the tip 62 of the plunger member 60.

Pin and socket contact removal from an electrical connector, such as that illustrated in FIG. 4, is easily accomplished by use of the removal tool 10 of the present invention. Socket contact removal is illustrated in detail by the cross-section of FIG. 6 and reference is directed thereto. There a socket contact 90 is to be removed from a female portion of an electrical connector having a contact retention device provided by the dielectric member 95 and the separable dielectric member 96 with the resilient retaining collar 97. The contact retention device may be of the type described in Pat. No. 3,477,061 issued on Nov. 4, 1969 to C. D. Stephenson, and reference is made thereto for a complete description of a typical contact retention device. In essence, separation of the member 96 from member 95 removes the resilient retention collar 97 from the restraint of member 95; allowing the collar 97 to expand for removal of the

contact 90. The tip 62 of the plunger member 60 is inserted into the socket 90 to the bottom thereof and then simply manually pushed outwardly, to the left as viewed in FIG. 6, while the tool 10 is grasped at handle cover 15. The ferrule portion 46 bears against the socket 90 forcing the slide member 40 to a retracted position within the body member 20 against the bias of spring 80. The guide surface 41 of member 40 and projecting holder sleeve 30 assures an even axial compression of the spring 80. Note that the slender plunger member 60 is surrounded either by the socket member 90 or the ferrule portion 46 throughout the removal operation. This assures protection of the delicate plunger member 60 and provides additional compressive strength therefore. The ferrule portion 46 may have an outside diameter approximating that of the socket contact 90 to follow the socket contact 90 and plunger member 60 through the dielectric member 95 for complete removal of the socket contact 90. After disengagement of the tool from the socket contact 90, the bias of spring 80 will return the slide member 40 and ferrule 46 to a protective position with respect to the plunger member 60.

Pin contact removal is described with reference to the FIG. 7. The slide member must first be slid forward to an extended position determined by the J-slot 34 with the ferrule portion 46 beyond the tip 62 of the plunger member 60. Preferably, this may be accomplished by grasping the reduced portion 44 at the knurled surface 49. As the slide member 40 slides forward, the bayonet pin 70 travels along the elongated slot 33 until reaching the juncture with the J-slot 34. Then the slide member 40 is rotated to bring the bayonet pin 70 within the J-slot 34, as shown in FIG. 7. The resulting extended position is locked by engagement of pin 70 within J-slot 34 against the bias of coil spring 85 which has been compressed between the retention collar 27 of body member 20 and the ledge 45 of slide member 40. The reduced portion 44 within the coil spring 85 provides a guideway assuring that the coil spring 85 is axially and evenly compressed. The dimensions of the J-slot 34 and the length of the elongated slot 33 are chosen to provide an extended position of the ferrule 46 at a sufficient distance beyond the tip 62 of the plunger member 60 for reception of a pin contact 98 so that an end of the ferrule portion 46 bears against the shoulder 99 of the contact. Again, removal is by simply pushing inward (to the left in FIG. 7) and through the dielectric member 100, which has a contact retention device (not shown) as previously described.

The plunger member 60 may be readily replaced upon becoming bent or damaged by utilization of a pliers or similar hand tool to forcefully pull it outward from its force fit within the insert 65 and the holder sleeve 30. A new plunger member 60 may be inserted by simply forcing it inward into the insert 65. Assembly and disassembly of the entire tool 10 may be accomplished by forcefully removing the body member 20 from within the handle cover 15. Then the roll pin 29 and bayonet pin 70 may be removed and the plug member 28, slide member 40, plunger member 60 and coil springs 80, 85, may be removed by sliding outward to the rear, to the right as viewed in FIG. 5. Assembly, of course, is exactly the reverse. In this manner the tool 10, according to the present invention, may be readily assembled and disassembled for replacement of worn and damaged parts.

While particular embodiments of the invention have been illustrated and described, it will be obvious to those skilled in the art that changes and modifications may be made without departing from the invention in its broader aspects, and therefore, the aim in the appended claims is to cover all such changes and modifications as followed in the true spirit and scope of the invention.

I claim:

1. A tool for pin and socket removal, comprising in combination:
a hollow tubular body member adapted to be held manually, said body having an interior chamber with an open end and a closed end;
a slide member in said chamber for travel between an extended position and a retracted position, said slide extending through said open end and including a ferrule portion beyond said body, said slide and ferrule having an axial bore therethrough;
and a slender plunger member in said bore and bottomed on said closed end, said plunger extending to a tip beyond said body for insertion into a socket and removal thereof by pushing, said retracted position of said slide allowing said tip to engage the bottom of said socket while said ferrule protects and braces said plunger, and said extended position of said slide presenting said ferrule beyond said tip for reception of a pin within said ferrule and removal thereof by pushing against a shoulder of said pin.
2. A tool according to claim 1 wherein the outside diameters of said plunger and ferrule correspond to those of a pin and socket, respectively.
3. A tool according to claim 1 including lock means for holding said slide at said extended position.
4. A tool according to claim 3 including a first bias means urging said slide toward said extended position and a second bias means urging said slide toward said retracted position, said lock means holding said slide at said extended position against the urging of said second bias means, and said retracted position being accomplished by release of said lock means to allow a socket to force said ferrule inward along said plunger against the urging of said first bias means.
5. A tool according to claim 4 wherein the said body includes a retention collar at said open end to captivate said slide within said cavity, and wherein said first and second bias means are provided by coil springs between said closed end, slide, and retention collar, respectively.
6. A tool according to claim 5 wherein said body has an elongated longitudinal slot with an intersecting J-slot transverse thereto, and said slide has a bayonet pin extending radially therefrom for engagement within said elongated slot and J-slot, said bayonet pin sliding along said longitudinal slot as said slide travels between said retracted position and extended position, said J-slot and bayonet pin providing said lock means by rotation of said slide for engagement therebetween.
7. A tool according to claim 6 wherein the said slide includes a reduced portion extending through said collar to said ferrule, said reduced portion having a knurled surface for manually gripping and rotating said slide.
8. A tool according to claim 7 wherein said closed end of said body is a removable plug to facilitate assembly and disassembly of the said tool.
9. A tool according to claim 8 wherein said plug includes a holder sleeve projecting into said cavity, said holder sleeve including a nylon insert, and said plunger having a force-fitted reception therein affording ready replacement thereof, and said holder sleeve being of a diameter smaller than said coil spring of said first biasing means for reception therein to provide guidance upon compression thereof.
10. A tool according to claim 9 wherein said body includes a handle cover thereover, said cover having a tight-fit thereon, yet, being removable for assembly and disassembly of said tool.
11. A tool useful in removing both sockets and pins from the socket and pin support passages of an electrical connector, said tool comprising:
an elongated plunger member having one extremity of a first portion thereof dimensioned to fit within a socket of a given electrical connector;
a tubular member surrounding said pin at said one ex-

tremity in close sliding relationship thereto, the internal bore of said tubular member being dimensioned to freely accept a pin of said given electrical connector with said tubular member having external dimensions permitting at least a first portion thereof which is most closely associated with said one extremity of said pin to pass into the support passages of said given electrical connector;

a manually manipulatable handle structure supporting said plunger and tubular members in movable relationship to one another;

a means for selectively restraining said plunger and tubular members from motion relative to one another when the longitudinal extremity of the first portion of said tubular member closest to said one extremity of said plunger extends beyond said one extremity of said plunger whereby said tool is useful in removing pins from said given electrical con-

nectors when the relative motion between said member is restrained and useful in removing socket members from said given electrical connector when said relative motion is unrestrained.

- 5 12. Apparatus according to claim 1 wherein said handle structure includes spring biasing means coupled between said tubular member and said plunger member to maintain said longitudinal extremity of said tubular member yieldably displaced from said one extremity of said plunger with the plunger passing through the entirety of the tubular bore at said longitudinal extremity thereof.
